(57) **CLAIM**

The ornamental design for a supplying port member for toner pack, as shown and described.

DESCRIPTION

FIG. 1 is a front view of a supplying port member for toner pack showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a perspective view thereof; and,

FIG. 8 is another perspective view thereof.

The broken lines in the drawings illustrate portions of the supplying port member for toner pack which form no part of the claimed design.

1 Claim, 8 Drawing Sheets
